CARBONATING APPARATUS

Frank M. Iannelli, East Orange, N. J.

Application June 11, 1954, Serial No. 436,047

6 Claims. (Cl. 261—70)

This invention relates to carbonating apparatus and more particularly to new and useful improvements in means for forcing the water or other potable liquid into the mixing chamber and for preconditioning the water or liquid prior to mixing with the carbonating gas.

As city water supply pressures are not ordinarily high enough for efficient carbonating, it has been customary to provide motor driven pumping apparatus to force the water or liquid into the carbonating chamber of the carbonating apparatus against the pressure of the carbonating gas. Obviously, such automatic pumping apparatus is bulky and heavy and in operation takes up considerable space and consumes energy so that its relatively high first cost and operating and maintenance costs are objectionable.

It is a prime object of the present invention to provide an improved water carbonating apparatus capable of operating successfully without the necessity of such complicated and expensive motor drive pumping apparatus.

Another object of the invention is to provide a water carbonating apparatus in which the supply of carbonating gas is used for forcing the water into the carbonating chamber and for preconditioning the water prior to entering the carbonating chamber as well as for carbonating the water in the chamber.

A further object of the invention is to provide a water carbonating apparatus with means for preconditioning the water or liquid before it enters the carbonating or mixing chamber in order to facilitate carbonization thereof.

Still another object of the invention is to provide a carbonating apparatus of this kind wherein the mixing chamber is separate from the distributing chamber so that the carbonated water is discharged in a smooth, nonturbulent stream.

It is a further object of the invention to provide a water carbonating apparatus, the essential parts of which are formed of moldable plastic material.

It is further proposed to produce a water carbonating apparatus which is simple, compact and rugged in construction, highly efficient in operation and which can be manufactured and sold at a reasonable cost.

Other objects and advantages of the invention will be apparent from the description thereof to follow taken in connection with the accompanying drawings in which—

Figure 1 is a top plan view of a carbonating apparatus made in accordance with the present invention, parts being shown diagrammatically.

Figure 2 is a vertical sectional view thereof taken approximately on the plane of the line 2—2 of Figure 1, parts being omitted.

Figure 3 is a side elevational view thereof, parts being shown broken away.

Figure 4 is a horizontal sectional view taken approximately on the plane of the line 4—4 of Figure 2, parts being shown broken away.

Figure 5 is a bottom plan view of the top closure plate.

Figure 6 is a vertical sectional view taken through the center of the valve device for controlling the entrance of carbonating gas into the water reservoir, parts being shown in elevation.

The apparatus illustrated in the drawings comprises generally a water or liquid reservoir or tank connected to

2

a source of water supply and a source of carbon dioxide gas supply, and a distributing tank inside of which is a separate mixing chamber connected to the same source of gas. The water and gas are mixed in the mixing chamber and the carbonated water is delivered to a dispensing faucet from the distributing tank.

Referring particularly to Figure 2, the water or liquid reservoir or tank comprises a cylinder 1 closed at its bottom by a base 2 and being seated in and sealed by a socket portion 3 formed on the floor of the base, adjacent one end thereof. The base is substantially rectangular in plan with a peripheral flange 4 and with rounded ends.

The distributing tank comprises a cylinder 5, similar to cylinder 1 but larger in diameter. The bottom of the cylinder 5 is closed by the base 2 and is seated in and sealed by a socket portion 6 adjacent the socket portion 3. The top of the cylinder 5 is closed by a cover 7, of a shape similar to the shape of the base 2 and is provided with a peripheral flange 8 and a circular opening 9, adjacent one end thereof. The wall of the opening is formed with a shoulder 10. The top of the cylinder seats in and is sealed by a socket portion 11 formed on the under side of the cover. The top of cylinder 1 extends into the opening 9 in the cover 7 and is closed by a closure and mounting plate 12 which is fastened to the cover by screws 13. A gasket 14 seated on the shoulder 10 seals the juncture between the opening 9 and the closure plate 12.

The mixing chamber comprises a cylindrical wall 15 arranged inside and separate from the distributing tank cylinder 5. The bottom of cylinder 15 is closed by the floor of the base 2 and is seated in a circular groove 16 formed in the floor of the base. The top of cylinder 15 is closed by the cover 7 and is seated in a circular groove 17 formed in the roof of the cover.

The parts of the carbonating apparatus thus far described, excepting the screws and gasket 4, are formed of moldable plastic material. A suitable plastic material for this purpose is Tenite which has been found to have the necessary strength and leaves no taste.

The closure plate 12 is formed with a threaded inlet passage 18, over the cylinder 1, and threaded into said passage is one end of a tubular coupling 19 for supporting an inlet pipe 20 extending into the interior of the cylinder 1. A pipe 21 has one end connected to the other end of the coupling and has its other end connected to a source of water supply. A check valve 22 is interposed in the pipe 21 to prevent reverse flow of water. Plate 12 is formed with a passage or conduit 23 extending along the plate from the end thereof positioned over the mixing chamber 15 inwardly to a point positioned over the cylinder 1, where it terminates in a threaded passage 24 extending at right angles and communicating with the interior of the cylinder 1. A check valve 25 is threaded into the passage 24 and depends into the interior of the cylinder 1 for connecting an outlet pipe 26 with the passage, the outlet pipe depending into the cylinder 1 with its inlet end positioned near the bottom of the tank. The outer end of the conduit 23 is plugged as indicated at 27. Adjacent its outer end, the conduit 23 communicates with a threaded passage 28 formed in the closure plate 12, the passage being aligned with an opening 29 formed in the cover 7 above the mixing chamber 15. A sealing gasket 30 is interposed between the cover 7 and the closure plate 12 around the opening 29. A short pipe 31 is threaded into the passage 28 and extends through the opening 29 where it is provided with a ball ring 32 for sealing the pipe in the opening. The pipe leads into the interior of the mixing chamber 15 to permit water to fall into the interior of the chamber, in cascading fashion, in order to agitate the water in the chamber.

Cylinder 15 is formed with top and bottom openings 33 and 34, respectively, to permit the water to flow from the chamber to the distributing tank 5.

A discharge pipe 35 in the distributing tank 5, having its inlet end near the bottom of the tank, leads to a dispensing faucet 36. On the cover 7, above the distributing tank, there is supported a conventional relief valve 37 provided with a vent 38 leading to the atmosphere in the tank 5, at a pressure in excess of, for example 70 pounds per square inch, to escape while the water flows therein.

In the water reservoir 1, there is operatively arranged an inlet valve 39. This valve includes an elongated hollow casing or tubular body 40 open at its bottom end and open at its top. A tubular extension 41, of reduced diameter, is formed on the open top end of the casing 40, providing a shoulder 42 on the casing. The extension is telescoped in a tubular coupling member 43 extending through an opening 44 in the closure plate 12 over the reservoir 1, and clamped to the plate by a nut 45. The coupling member is formed with an annular flange 46 on its inner end adapted to seat on the shoulder 42 of the tubular casing 40. Flange 46 forms a seat for a packing ring 47 around the upper end of the tubular casing 40. A gasket 48 is interposed between the nut 45 and the top of the closure plate for sealing the outer end of the opening 44 and with a similar gasket 49 seated on a shoulder 50 formed on the coupling member for sealing the inner end of the opening. A float in the form of a hollow plastic cylindrical casing or tube 51, closed at its top and bottom, is slidably and floatingly supported by the tubular casing 40. This hollow casing 51 is provided with a tubular extension 52 formed integrally with its closed top portion, the extension being open at the top. A sleeve member 53 is fastened to the inner surface of the tubular extension 52 by welding or otherwise and projects outwardly thereof. Adjacent its top, the hollow casing 40 is formed with a plurality of small holes 54 adapted to be closed by the sleeve member 53, when the latter is carried upwardly along the casing 40 by the floating casing 51 into contact with the packing ring 47. A headed extension 55 on the bottom end of the tubular casing 40 coacts with a perforated disc 56 fitted in the tubular extension 52 of the valve casing to limit the downward movement of the casing.

A main supply pipe 57 (Figure 1) leads to a supply of carbon dioxide (not shown) held confined under pressure, for example, 100 pounds, and to a T-fitting 58. A conduit pipe 59 is connected at one end to one side of the T-fitting and at its other end opens into the tubular coupling 43 of the inlet valve 39 in the reservoir 1, and is connected to the coupling by a nut 60. A pressure reducing and regulating valve 61 is interposed in the pipe 59 adjacent the T-fitting for controlling the pressure of gas passing therethrough. Another 2-way valve 62 is interposed in pipe 59 adjacent its entrance into the coupling member 43 for controlling the passage of gas through the holes 54 in the inlet valve 39 in the reservoir 1, and for controlling the passage of air through a vent 63 in the valve 62 leading to the holes 54.

Another conduit pipe 64 having a check valve 64a is connected at one end to the other side of the T-fitting 58 and at its other end to an inlet pipe 65 in the mixing chamber 15. Pipe 65 extends to the bottom of the chamber through and below a plate 66 secured to the wall of the chamber adjacent its bottom end. The plate is formed with a plurality of holes 67 which serve to separate the gas into a large number of minute streams. A pressure regulating valve 68 is interposed in the pipe 64 and may be adjusted for a predetermined pressure in the mixing chamber 15. The space above the carbonated water will also contain gas which comes into intimate contact with the water as it falls from the pipe 31.

Provision is made for regulating the quantity of water

in the reservoir 1 and comprises electrical apparatus housed in an insulating casing 69 mounted in an opening 70 in the cover 7 above the distributing tank 5, including a pair of elongated electrodes 71 and 72 depending to different levels in the tank. The difference in levels between the bottom of these electrodes controls the operation of the solenoid 78 to be described. Conductors 73 and 74 connected to terminal posts 75 and 76, respectively, on the respective electrodes 71 and 72, connect the electrodes to a "Warwick" switch 77 which controls a solenoid 78 which in turn controls the operation of the valve 62 in pipe 59. When the water in reservoir 5 falls below the level of the lower end of electrode 72, the solenoid 78 is energized to operate the valve 62 to permit gas pressure, at for example 100 pounds pressure per square inch, to flow into the reservoir, as hereinafter described.

In operation during initial filling of the reservoir 1, the gas pressure is turned off, the air vent 63 is open and the float valve casing 51 is normally in downward position leaving the holes 54 in valve 39 uncovered. Water is then allowed to flow from the water supply through the supply pipe 21, which is provided with the check valve 22 to prevent reverse flow, and through the inlet pipe 20 into the reservoir 1, until the float valve casing 51 is raised and the sleeve member 53 engages the packing ring 47 and closes off the holes 54 in valve 39.

The further venting of air is thereby prevented so as to prevent further rise in the level of water in the reservoir. The water will then continue to pass from the reservoir 1 under its own pressure through pipe 26, check valve 25, passages 23 and 31 into the mixing chamber 15 and thence through holes 34 into the tank 5 until the water level reaches the upper electrode 71. The electrical circuit including the solenoid 78 and the liquid level control apparatus comprising the electrodes 71 and 72 and "Warwick" switch 77, is then plugged in, the solenoid 78 is deenergized, the gas inlet of valve 62 is closed and the air vent 63 is opened. If the water pressure in the supply pipe should be so low that the water level in tank 5 does not reach the upper electrode, the solenoid becomes energized when the circuit is plugged in, the gas inlet of valve 62 is open and vent 63 is closed; and when the gas is turned on, gas will enter the reservoir 1 at, for example, 100 pounds pressure, so as to force more water into the tank 5 until the water level reaches the upper electrode 71 whereupon the solenoid is deenergized. The gas is turned on but gas will enter only the tank 5 and the mixing chamber, through conduit pipe 64 and inlet pipe 65 for carbonating the water, because the vent 63 is maintained open, due to the deenergization of the solenoid of valve 62 as the result of the contact of the water with the upper electrode 71, and the closed gas inlet of valve 62 prevents passage of gas pressure into the reservoir from pipe 59. When carbonated water is drawn from the tank 5 through the pipe 35 and faucet 36, and the water level drops below the lower electrode 72, the solenoid 78 will be energized so as to actuate the valve 62 to shut off the vent 63 and to open the passage through the valve from the gas supply pipe 59 to the float valve 39. The gas pressure will force the float 51 downwardly against the buoyancy of the water in the tank so as to move the upper end of the sleeve 53 out of contact with the gasket 47 and permit gas pressure to enter the tank through the openings 54, it being remembered that at the same time the water will flow from the tank 1 through the pipe 26 into the tank 5 so as to relieve the effect of the water on the float and permit the float to completely open the holes 54 without back pressure on the float. When sufficient water has passed from the reservoir 1 to the tank 5 to reach the upper electrode 71 the solenoid will be deenergized and the valve 62 will be actuated immediately to shut off the gas pressure from the tank 1 and simultaneously open the vent 63 so as to allow trapped gas in the tank 1 to escape through the holes 54 and vent 63 and permit the reservoir to be refilled with water from pipe 21 until the float sleeve

53 is again forced against the packing ring 47 to shut off further venting or escape of air. The apparatus is then ready for the next withdrawal of water from the tank 5 through the faucet 36.

It will be noted that the pressure of the gas on the water will cause the water to flow from the pipe 31 into the mixing chamber 15 in a cascade fashion in order to agitate the water in the mixing chamber where it is discharged through the opening 33 and 34 in the cylinder into distributing tank 5. The carbon dioxide gas from the supply pipe 64 enters the mixing chamber 15 under pressure through the inlet pipe 65 and up through the holes 67 in plate 66 for carbonating the turbulent water in the mixing chamber. By adjusting the valve 68 in pipe 64, the pressure of the gas from the main supply pipe 57 may be reduced to any desired pressure, for example, sixty pounds, which is desirably less than the pressure of the gas in pipe 59 supplying gas for the reservoir 1.

When the level of the water in the distributing tank 5 reaches electrode 71, the solenoid 78 becomes deenergized and operates the valve 62 to cut off the gas supply and at the same time vent the reservoir 1 to the atmosphere and thereby permit water to enter the reservoir 1 from the supply pipe 21.

When it is desired to use carbonated water the faucet 36 is opened and carbonated water will be delivered therefrom under pressure of the gas in the distributing tank 5. When the level of the liquid in the tank 5 drops below the bottom end of the electrode 72, the solenoid 78 becomes energized to operate the valve 62 so as to permit gas to flow into the reservoir 1 and force the water from the reservoir 1 into the distributing tank 5.

While I have illustrated and described the preferred embodiment of my invention, it is to be understood that changes in details of construction might be made without departing from the principle of the invention, and I desire to be limited only by the state of the prior art and the appended claims.

What I claim is:

1. A carbonating apparatus comprising a reservoir having an inlet with a check valve for liquid under pressure from a supply of liquid to be carbonated, means including a control valve for controlling flow of gas under pressure into said reservoir and for venting of gas from said reservoir to the atmosphere, alternately, a closed liquid distributing tank, means for establishing communication between said reservoir and said tank including an outlet pipe in the reservoir, a check valve in said outlet pipe and an inlet passage in said tank adjacent the top thereof above the liquid level therein communicating with said outlet pipe at the discharge side of said check valve whereby the liquid from said reservoir may flow through said outlet pipe and said inlet passage into the tank, a gas inlet pipe for the tank to communicate with a source of carbon dioxide gas for admitting gas to the tank adjacent the bottom thereof to carbonate the liquid therein, a discharge pipe for the tank with its entrance end adjacent the bottom of the tank, means providing a supply of carbon dioxide gas to the reservoir through the first named means under pressure substantially greater than the pressure of the liquid supply to force the liquid in the reservoir from the reservoir into the tank, means providing a constant supply of carbon dioxide to said gas inlet pipe that leads to said tank at a pressure substantially less than the gas pressure supplied to said reservoir, and valve means for relieving gas pressure in said tank in excess of a predetermined maximum pressure.

2. A carbonating apparatus as defined in claim 1 with the addition of means for causing actuation of said control valve to permit flow of carbon dioxide gas into said reservoir when the carbonated liquid in said tank reaches a predetermined low level and thereby force liquid from said reservoir into said tank and to cut off carbon dioxide from said reservoir and simultaneously vent gas from

said reservoir when the carbonated liquid in said tank reaches a predetermined high level and thereby admit liquid to be carbonated into the reservoir.

3. A carbonating apparatus as defined in claim 1 with the addition of a wall within said tank providing a separate mixing chamber into which extends said gas inlet pipe and having openings at its lower end communicating with the interior of the tank.

4. A carbonating apparatus as defined in claim 1 with the addition of a wall within said tank providing a separate mixing chamber into which extends said gas inlet pipe and having openings at its lower end communicating with the interior of the tank, and wherein said inlet passage leads into the upper end of said mixing chamber above the level of the liquid therein, and said inlet pipe for carbon dioxide gas has its outlet end opening into the lower end of said mixing chamber.

5. A carbonating apparatus as defined in claim 1 wherein said reservoir has a common inlet port and vent for gas under pressure, the control valve of the first named means communicates with said port to vent said reservoir and admit carbon dioxide into the reservoir, alternately, and with the addition of other valve means associated with said common inlet port and vent between said control valve and said reservoir, and a float connected to said other valve means in said reservoir so that said float is actuated upwardly by liquid in said reservoir to actuate said other valve means to close said inlet port against the escape of gas from said reservoir when the liquid level in the reservoir reaches a predetermined point, thereby to prevent further rise of the liquid level in the reservoir, and gas under pressure entering said common inlet port and vent from said control valve forces said float downwardly against the influence on said float of said liquid in the reservoir to open said common inlet port and vent and thereby permit inflow of gas under pressure through said control valve and said common inlet port and vent into said reservoir.

6. A carbonating apparatus as defined in claim 1 wherein said reservoir has a common inlet port and vent for gas under pressure, the control valve of the first-named means communicates with said port to vent said reservoir and admit carbon dioxide gas into the reservoir, alternately, and with the addition of other valve means associated with said common inlet port and vent and a float connected to said other valve means in said reservoir, said float being actuated by liquid in said reservoir to close said common inlet port and vent against the escape of gas from said reservoir when the liquid level in the reservoir reaches a predetermined point thereby to prevent further rise of the liquid level in the reservoir, and said float and other valve means being actuated by gas under pressure that enters said common inlet port and vent from said control valve of the first-named means to open said common inlet port and vent and thereby permit inflow of gas under pressure into said reservoir, and means for causing actuation of said control valve to permit flow of carbon dioxide gas through said common inlet port and vent into said reservoir when the carbonated liquid in said tank reaches a predetermined low level and thereby force liquid from said reservoir into said tank, and to cut off carbon dioxide gas from said common inlet port and vent and simultaneously vent gas from said reservoir through said common inlet port and vent when the carbonated liquid in said tank reaches a predetermined high level and thereby admit liquid to be carbonated into the reservoir.
